UNITED STATES PATENT OFFICE

ALBERT G. HARMS, OF CHICAGO, ILLINOIS

LOOP AERIAL

Application filed April 12, 1926. Serial No. 101,325.

My invention has reference to loop aerials such as are used in connection with radio receiving sets or other similar apparatus for collecting electrical waves in radio or wireless communication.

The invention relates to that type of loop aerial shown and described in my co-pending application, filed December 24, 1925, under Serial No. 77,568, and more particularly to 10 that type having an area about which the wires are wound to wholly enclose said area or a substantially continuous winding throughout the entire area, field, or surrounding sides thereof but embodies in addition, 15 a novel loop aerial in which a series of substantially independent loops are disposed one within the other in fixed or movable relation and especially wherein said loops are rotatable one with respect to the other to vary 20 their angular relation when movable relatively, and in which said loops or the loop as an entirety embodying a series of loops disposed successively one within the other, are adapted to be connected electrically or 25 inductively and in parallel, series or multiple for various purposes, as will be hereinafter more fully set forth, such as for disposing them in a relation to produce a variable inductance for increasing or decreasing the 30 signal strength, tonal quality, or clarity of the reception; for tuning in or out certain waves of different lengths in the manner of a trap—that is, different stations; for varying the length of wire in the coils, the number of coils 35 embodied in the device as a whole and its flexibility or scope of reception and tuning ability or qualities, as well as the relative lengths, sizes, and inductances of the coils or windings of the coils and for other useful 40 purposes and advantages as will be apparent as the description proceeds.

In the accompanying drawings:—

Fig. 1 is an elevation of a loop aerial embodying principles of my invention and illustrating the same in one single form.

Fig. 2 is a top plan view of the device as shown in Fig. 1 with one form of winding.

Fig. 3 is a top plan view of a form in which the inner or auxiliary loops or windings are movable angularly or rotatably with respect 50 to an outer loop or winding or any of the windings outwardly thereof and showing an inner loop or winding shifted with respect to an outer one.

Fig. 4 is a diagrammatic elevation showing 55 the loops or windings connected in series.

Fig. 5 is a diagrammatic perspective view showing the relation of the loops when mounted one within the other in fixed or movable relation, and

Fig. 6 is a diagrammatic elevation similar 60 to Fig. 4 but showing the loops connected in multiple.

Referring to the drawings in detail, 65 indicates a base on which the aerial or radio antenna 8 is mounted, preferably to turn as by means of a frame including an upright 9 having a pivot portion engaged in a socket 10 in the base. The upright 9 may have a series of successively reduced portions or 70 tubes 11 forming shoulders 12 against which end members 13 in the form of suitable plates or disks of rectangular or other shape are secured either in fixed relation or in such a manner that the top and bottom end members 75 of the frames or opposed pair of plates may be turned or rotated one within the other in different angular relation. The plates 13 are preferably provided with notches or other receiving means 14 for continuous windings 80 or coils 15 of a plurality of loops or windings placed one within the other, the series of loops forming a single loop aerial in its entirety. If preferred, the plates 13 may be arranged 85 in any other suitable relation or in contact, and the coils 16 thereof are preferably extended diagonally of the respective plates or frames and may be arranged with the leads or extremities thereof free, as indicated at 17 in Fig. 2 of the drawings, or may be connected 90

in series as indicated at 18 in Fig. 4 of the drawings or in multiple or parallel, as shown by the connections 19 in Fig. 6 of the drawings.

- 5 The coils of the respective loops 15 may be equi-distantly spaced apart as shown in Figs. 1, 2, and 3, in which event the inductance of the respective loops placed one within the other vary, owing to the different 10 lengths of wire carried thereby, the inner loops being smaller and of less inductance than the outer loops, so that the loops are of progressively less inductance inwardly and of greater inductance outwardly. While the 15 loops may be maintained in fixed relation with their coils all extending in the same direction as shown in Figs. 1 and 2, or otherwise, they may be arranged at any other desired angular relation and when arranged 20 to turn relatively, may be disposed in different angular relations as illustrated in Fig. 3. All of the loops are of the type wherein the windings extend substantially entirely around the field or loop as shown and described in my prior application above alluded to, the loops being parallel and progressively decreasing in width from the center to the opposite sides or increasing in width and size from opposite sides to the center in opposite 25 directions, in addition to being disposed closely adjacent. While I have shown notches for receiving the wires on the respective end members or plates 13, it is to be understood that any other suitable wire-receiving and 30 retaining means for the windings may be provided.

In Fig. 3 of the drawings one of the inner loops is shown turned with respect to the adjacent outer loop for the purpose of raising or lowering the inductance value and for tuning as in connection with a variometer. 35 Alternate loops may be connected inductively or electrically, according to the result to be obtained. If all of the loops are connected inductively, the inductance, of course, will be greater and where alternate loops are connected inductively and electrically, for instance, the outer and third inner loop of the plurality of loops composing the aerial may 40 be inductively connected and the second and fourth or other loops electrically connected to assist in energizing the inductively connected loops and increasing the inductive effect by catching the waves and transmitting 45 the same to the inductively connected loops. This provides for greater signal strength and 50 clearer and sharper tone qualities. This, as well as the arrangement of having the loops adjustable angularly, serves the purpose of 55 tuning by bucking or cutting in or out one or more stations after tuning the same in or by arranging the loops or coils in such a manner as to reduce the inductance. When the 60 coils are connected in multiple, the inductance 65 balances, being an average of the four, five,

or other number of loops which may be employed, thus rendering the device very flexible in inductance and receptive value. In either case there is provided a closed loop or loops within a loop and thus loops may be arranged with their windings or coils in the same direction, in different angular relation, or arranged and connected so that the windings are arranged in the opposite direction with a variance of 180 degrees and fixed or variable 70 to each other.

Furthermore, the inductance of the respective loops may be variable or equal and in the latter case shown more especially in Fig. 5, the windings are closer together as they 75 approach the inner loop. In this way, the same length of wiring may be arranged in each loop owing to the coils or windings thereof being closer together as the loops are progressively decreased in size. In this way 80 the inductance of the loops may be made equal instead of being varied or progressively decreasing inwardly, this depending upon the length of wire or number of coils in the 85 respective loops. While I have shown the 90 end members or plates 13 spaced apart, they may be arranged in other suitable relation and can be made thicker and arranged in contact whether mounted in fixed relation or adapted to turn relatively, with the same 95 results as heretofore pointed out.

While I have shown and described my invention in a preferred form, I am aware that various modifications and changes may be made therein without departing from the 100 principles of the invention, the scope of which is to be determined from the appended claims. It also has been found in practice that by placing a variable condenser in shunt 105 with one or more of the loops not electrically connected with the set, a broadcast station can be tuned in or tuned out, i. e. eliminated, by adjusting the condenser, that is, by varying the capacity of the condenser, thereby 110 broadening the frequency range of the loop 115 to receive on higher or lower frequencies without tapping or cutting in or out parts or turns of the loop.

I claim as my invention:

1. A loop aerial having more than two loops mounted successively one within another in decreasing size and each having a continuously extending coil winding with the coils thereof equidistantly spaced apart in parallel relation and supported on successive enlarged portions.

2. A loop aerial having at least four loops contained in spaced relation one within another, each loop having the coils relatively closely wound in spaced relation and extending entirely around the area thereof, successively enlarged posts fitting one within another and each supporting a loop.

3. A loop aerial including at least four loops successively placed one within the

other and having the wiring thereof extending continuously around each on all sides in coils with the sides approaching each other and the windings adapted to varying lengths, and for variable connection inductively or in opposition, each loop having a tube and the tubes being successively smaller to movably fit one within another whereby each loop may be adjusted or turned on a vertical axis angularly with respect to the other loops.

10 ALBERT G. HARMS.
